F. BARR.

SHADE SUPPORT.

APPLICATION FILED JULY 23, 1915.

1,157,201.

Patented Oct. 19, 1915.

UNITED STATES PATENT OFFICE.

FREDERIC BARR, OF WOODHAVEN, NEW YORK.

SHADE-SUPPORT.

1,157,201.

Specification of Letters Patent. Patented Oct. 19, 1915.

Application filed July 23, 1915. Serial No. 41,577.

To all whom it may concern:

Be it known that I, FREDERIC BARR, a citizen of the United States, and resident of Woodhaven, in the county of Queens and State of New York, have invented certain new and useful Shade-Supports, of which the following is a specification.

My present invention aims to do away with the need for the clumsy and more or less unsightly attachments heretofore employed for supporting the shades of electric lamps and similar fixtures and to provide simple and inexpensive means for this purpose which will be reliable and practical in use and neat and unobtrusive in appearance. These objects I accomplish by using screws for directly supporting the shade, which screws are passed through openings in the neck of the shade and engage in screw seats in a member provided for that purpose, said member or the screws themselves having a bearing on a shoulder on the fixture. This shoulder is present in the ordinary lamp socket in the form of an outstanding annular bead usually provided near the lower end of the socket shell. The screw seats for the supporting screws may be provided in a ring located inside or outside the neck of the shade and this ring may be substantially continuous or be broken up into segments, as will later appear.

Various other features will appear as the specification proceeds.

In the drawing accompanying this specification I have illustrated several practical forms the invention may take, but it will be understood that various changes and modifications may be made without departing from the true spirit and scope of the invention.

In the drawing: Figure 1 is a view in side elevation of an embodiment of the invention as applied to an electric lamp fixture. Fig. 2 is a vertical sectional view of the same. Fig. 3 is a horizontal sectional view taken substantially on the plane of the line 3—3 of Fig. 2. Fig. 4 is a detached perspective view of the screw seat ring employed in this first form of the invention. Fig. 5 is a horizontal sectional view taken on a plane similar to that of Fig. 3 of a modification wherein the screw seat ring is discontinuous or segmental in form. Fig. 5^a is a detail perspective view of a segment and supporting

screw of this latter form of the invention. Fig. 6 is a side elevation of a form of the invention wherein the screw seat ring is placed on the outside of the shade. Fig. 7 is a vertical sectional view of this form. Fig. 8 is a detached detail view of the screw seat ring and supporting screws in this latter construction. Figs. 9 and 10 are vertical sectional and detail views of another form of construction and Fig. 11 is a detail view of another modification.

The lamp socket 10, illustrated, is of typical construction, provided with the usual outstanding annular bead 11, near the lower end thereof.

The shade 15, which may vary in shape to meet different requirements, is made with a neck portion 16, to fit over the bead end of the lamp socket and this neck portion is provided with a suitable number of openings 17, (usually three) for the supporting screws. This neck portion of the shade is preferably but very little larger in diameter than the bead of the socket so as to make a neat joint with the socket and so that relatively short supporting screws can be used.

The supporting screws, designated 18, extend through the openings in the neck of the shade and engage in screw seats in a member or members provided for that purpose.

In the first form of the invention illustrated, this screw seat member is in the form of a ring 19, located inside the neck of the shade and provided with screw seats 20, in line with the openings 17 in the shade. This ring, while substantially continuous, may be broken at one point, as indicated at 21, to permit its being sprung over the bead of the socket.

In using the form of the invention just described, the screw seat ring is sprung up over the bead or shoulder of the socket, or otherwise engaged with the socket so as to rest upon and be supported by said bead or shoulder. The shade is then engaged over the socket far enough to bring the openings in the neck of the shade into register with the screw seats in the ring and the supporting screws are then inserted through the openings in the shade into engagement with the screw seats in the ring. The shade is now firmly supported but can be readily removed when desired by simply loosening the supporting screws from engagement with the ring.

The screw seat member can be made of relatively light, inexpensive material, since the necessary bearing for the screws can be obtained by simply bushing up the material around the screw seats, substantially as indicated.

The parts are preferably so proportioned that the neck of the shade will confine the screw seat ring to the fixture and prevent it from slipping down over the bead.

In Fig. 5 I have shown how the screw seat ring need not be continuous but may be broken up into segments 25, each segment having a seat 26, for one of the supporting screws. These segments bear on the shoulder of the fixture and constitute in effect a series of separate nuts for the screws. The continuous ring first described provides a substantially continuous and therefore somewhat more firm support for the shade, the ring in that case constituting in effect a series of interconnected nuts for the screws. These forms above described are particularly neat in appearance in that the only parts of the fastening means exposed are the heads of the supporting screws and these can be made relatively small and inconspicuous, or ornamented, as desired.

Figs. 6, 7 and 8 illustrate how the screw seat member may be located on the outside of the shade, said member being shown in this form as a split spring ring 28, encircling the neck of the shade and having screw seats 29, in line with the openings 30 in the shade. The supporting screws in this case engage directly with the shoulder on the fixture. The ring, in this construction, is held attached to the shade, when the shade is removed from the fixture, by means of the screws entering the openings in the shade and by the spring tension of the ring upon the neck of the shade. Additional means for holding the ring in place on the shade is illustrated in the form of a flange 32, on the shade, overstanding the upper edge of the ring.

From the foregoing it will be evident that my invention provides an extremely simple and inexpensive means of supporting lamp shades and which is applicable to standard fixtures now in use.

Still other forms the invention may take are illustrated in Figs. 9, 10 and 11. In the first two of these views, the nuts or ring segments 33, provided with the screw seats 20 and screw holes 34, are looped or doubled back upon themselves so as to embrace the upper edge of the shade. The nuts, in this form of construction also may be interconnected as a substantially continuous ring, as indicated in Fig. 11, where 36 indicates the looped nuts, connected as a continuous ring 35.

What I claim, is:

1. In combination with a fixture provided

with a bead, a shade having a neck portion encircling the fixture above the bead and provided with openings through the same, a ring about the fixture above the bead provided with screw seats in line with the openings in the neck of the shade and shade-supporting screws disposed in the openings in the neck of the shade and engaged in the screw seats in the ring. 70

2. In combination with a fixture provided with a bead, a shade having a neck portion encircling the fixture above the bead and provided with openings through the same, a substantially continuous ring about the fixture above the bead and provided with 80 screw seats in line with the openings in the neck of the shade and shade-supporting screws disposed in the openings in the neck of the shade and engaged in the screw seats in the ring. 75

3. In combination with a fixture provided with a bead, a shade having a neck portion encircling the fixture above the bead and provided with openings therethrough, nuts disposed between the fixture and the neck 90 of the shade and resting on said bead and supporting screws passed through the openings in the neck of the shade into engagement with said nuts. 85

4. The combination with a lamp shade 95 having a neck portion provided with openings therethrough, of a ring disposed closely adjacent and substantially engaging one face of the neck portion of said shade and provided with screw sockets in line with the 100 openings in the neck portion and supporting screws disposed in said openings in the neck portion and screwed into the screw sockets in the ring. 100

5. In shade supports, the combination with 105 a shade provided with openings through the neck portion thereof, of screw seat members provided with screw seats in line with the openings in the neck of the shade and having reversely directed portions looped over 110 the upper edge of the neck of the shade and supporting screws disposed in the openings in the neck of the shade and engaged in the screw seats aforesaid. 115

6. In shade supports, the combination of 115 a shade provided with openings through the neck portion thereof, inter-connected screw seat members located on one side of the neck of the shade, provided with screw seats in line with the openings in the neck 120 and having portions looped over the upper edge of the neck to the other side of the shade and supporting screws disposed in the openings in the neck and engaged with the screw seats aforesaid. 125

7. In shade supports, the combination of a shade provided with openings through the neck portion thereof, a split spring ring encircling the neck portion of the shade having screw seats in line with the openings in 130

the neck portion of the shade, a flange on
the neck portion of the shade overstanding
the upper edge of the ring and shade sup-
porting screws engaged in the screw seats
5 in the ring and passed through the openings
in the neck portion of the shade.

Signed at New York, in the county of

New York and State of New York, this 16th
day of July, A. D. 1915.

FREDERIC BARR.
